(57) **CLAIM**

We claim the ornamental design for a portion of a sawhorse combination, as shown and described.

DESCRIPTION

FIG. 1 is a perspective view of portion of a saw horse combination according to the invention.

FIG. 2 is a right side view of the portion of the saw horse combination.

FIG. 3 is a left side view of the portion of the saw horse combination.

FIG. 4 is a front elevational view of the portion of the saw horse combination.

FIG. 5 is a top plan view of the portion of the saw horse combination; and,

FIG. 6 is a bottom plan view of the portion of the saw horse combination.

The broken lines are for illustrative purposes only and form no part of claimed design.
